UNITED STATES PATENT OFFICE.

WILLIAM C. OASTLER, OF NEW YORK, N. Y.

ROTARY SCREEN FOR STONE, &c.

SPECIFICATION forming part of Letters Patent No. 255,325, dated March 21, 1882.

Application filed June 8, 1881. (No model.)

To all whom it may concern:

Be it known that I, WILLIAM CHURCHILL OASTLER, of the city of New York, in the county and State of New York, have invented 5 certain new and useful Improvements in Rotary Screens for Stone and other Substances, of which the following is a specification.

The principal object of my invention is to provide a screen for screening stone for roadways which will effectively separate the spalls or thin elongated chips from the pieces which are of approximately uniform dimensions, more nearly resembling the cube in form, and which are used for the wearing-surface of roadways.

15 To this end my invention consists in a rotary screen comprising a section or portion in which are elongated holes or slots which are so disposed that their lengths extend in different directions, some having their length parallel with the length of the screen, others having their length transverse to the length of the screen, and still others having their length oblique, so that they extend spirally in 20 the shell or cylindric body of the screen. The slots so disposed are more certain to catch and discharge all long chips and spalls than are slots the lengths of which all extend in one direction.

25 The invention also consists in a rotary screen comprising a portion or section having elongated holes or slots which are so disposed that their lengths extend in various or different directions, and comprising a second portion or 30 section surrounded or inclosed by an outer shield or casing which is imperforate opposite the holes or perforations in said second portion of the screen. If long pieces enter the holes or openings in the screen, they will strike 35 against the imperforate part of the shield or casing, and will thus be prevented from passing out said holes or openings, and as said screen is rotated will fall back into the screen and be delivered from the end thereof as unfit 40 for use unless again broken.

45 In the accompanying drawings, Figure 1 represents a side view, partly in section, of a screen embodying my invention; and Fig. 2 represents a section thereof upon the dotted 50 line xx , Fig. 1.

Similar letters of reference designate corresponding parts in both figures.

55 My improved screen may be attached to any description of crusher, and is supported by a central shaft, A, which rotates in suitable bearings in a frame-work (not here shown) in the ordinary way. The screen here shown comprises three sections or portions, B B' B². The first section, B, is covered with wire-gauze or other suitable finely perforated or reticulated 60 material, and separates from the crushed or broken stone, which enters at that end of the screen, the screenings, which are often used for binding material in the construction of roadways and for repairs.

65 From the section B the broken stone passes by gravity into the section B', in which are numerous elongated openings or slots, a , which are too narrow for the passage of pieces of stone which nearly approach the cube in form 70 and are desirable for making the wearing-surface of a roadway. The elongated holes or slots a are intended for the passage of all spalls and long, thin chips; and in order to render said holes or slots more effective they 75 are so disposed that their lengths extend in different directions upon the screen. For example, certain of said holes or slots are disposed so that their lengths are transverse to the length of the screen, certain others are disposed so that their lengths are lengthwise of the screen, and still others are disposed so that they extend obliquely or spirally on the screen. This arrangement of the holes or slots 80 is very advantageous, because all the spalls or long, thin chips are then far more likely to be caught by them, and a more thorough and effective separation is produced.

85 The portion B² of the screen, into which the broken stone passes after leaving the portion 90 B', has numerous round perforations or holes, b , which are of a size to permit the passage of pieces of a proper size to form the wearing-surface of a roadway—say about two (2) inches in diameter—and in order to prevent the passage through said holes of long pieces I inclose or surround the portion B² of the screen by an outer shield or casing, C, which is placed at a sufficient distance from the screen to leave 95 a space of about the size of the holes or per-

forations—say two (2) inches—between the screen and shield or casing.

The shield or casing is closed at the ends, and is here shown as secured to the screen by 5 knee or angle pieces, *c*; but it may be secured in any other suitable way. The shield or casing is here shown as composed of a number of separate pieces extending longitudinally upon the screen and placed at a little distance apart, 10 so as to leave a space between them a little more than equal to the diameter of the holes or perforations *b* and the space between the screen and the shield or casing.

The portions of the screen which come between 15 pieces which form the shield, or opposite the spaces between such pieces, are not perforated, and the pieces themselves which form the shield are wholly imperforate; but, instead of being composed of several pieces, 20 the shield or casing might be composed of one piece and be provided with openings or perforations entirely out of line with the perforations or holes in the screen. In any case the shield or casing should be imperforate opposite 25 the holes or perforations in the screen.

From the above description it will be clear that any pieces which approach nearly to the cube in form may readily pass through the holes or perforations *b* in the screen, thence 30 between the screen and the shield or casing, and finally out the spaces between the pieces of which the said shield or casing is composed, which I regard as openings in the shield or casing.

35 It will also be clear that if any long pieces enter the holes *b* they will strike against the shield or casing, which is imperforate opposite such holes, and can get no farther, and hence such pieces will drop back into the screen as 40 the latter rotates.

By my invention I provide a screen which

may be substituted for any ordinary rotary screen, and which is much more advantageous for separating stone for roadways than the screens heretofore in use.

45

Instead of the shield being made of separate sections with longitudinal openings between them, it may be made of sections of other form—as, for instance, in the form of bands—the holes *b* of the screen being arranged to correspond with and come within the said sections.

The sections or pieces which form the shield may be set somewhat eccentric to the periphery of the screen—that is, with one longitudinal edge at a greater distance from the screen than the 55 opposite edge—so as to facilitate the passage of pieces between the screen and shield. This would provide greater freedom of discharge for the spalls and chips and prevent choking.

What I claim as my invention, and desire to 60 secure by Letters Patent, is—

1. A rotary screen comprising a section or portion having in its periphery elongated holes or slots *a*, some of which extend transversely of the screen, others of which extend diagonally or obliquely of the screen, and still others of which extend longitudinally of the screen, substantially as specified.

2. A rotary screen comprising a portion or section having elongated holes or slots which 70 are so disposed that their lengths extend in various or different directions, and comprising a second portion surrounded or inclosed by an outer shield or casing which is imperforate opposite the holes or perforations in said second 75 portion of the screen, substantially as specified.

W. C. OASTLER.
